INSULATED PACKAGE

Lewis C. Pennebaker, Chattanooga, Tenn., assignor to O. B. Andrews Company, Chattanooga, Tenn., a corporation of Tennessee

Application June 14, 1946, Serial No. 676,751

6 Claims. (Cl. 229—14)

1

My invention relates to packages and more particularly to light weight, insulated packages, especially adapted to the shipment of perishables, such as frozen foods and the like, by air, in such a manner as to preserve them.

While in the prior art it has been customary to pack merchandise or articles, sensitive to temperature changes, in a plurality of containers or package one within the other, separated by insulating material or an air space, a number of disadvantages and defects in such packages have been noted. No effective light weight spacer or support has been developed which may be interposed between the containers, and which will, at all times, maintain the necessary clearances between containers or packages, prevent relative movement between inner and outer containers during handling or shipment, provide the requisite strength to properly support the inner container when heavily packed or when the package is given abusive treatment and preserve the insulating qualities of the space between containers.

If the clearances between containers are not maintained, the insulating qualities of the package deteriorate and the package loses its preservative characteristics. When support is not offered at the requisite points or where the interfitting of the elements is poor, the inner container or containers may be jostled about within the package during handling or shipping, and where they are loaded, such jostling about may cause rupture or breakdown of the inner container resulting in failure in both the packaging qualities and the insulating qualities of the package. Where the spacers are not sufficiently strong, or are improperly positioned or do not sufficiently cover the loaded areas, the weight of the packed material may cause rupture, breakdown or excessive sagging of the inner container or may result in crushing of the spacer or where the spaces are too numerous, too thick and too bulky, they will alter or destroy the insulating quality of the space between the containers.

Applicant, with a knowledge of all of these defects in and objections to the prior art, has for an object of his invention, the provision of an insulated package for the shipment or storage of perishables or other articles or merchandise sensitive to or affected by temperature changes.

Applicant has as another object of his invention, the provision of a heat insulated package with light weight, sturdy spacers which will provide a minimum of heat conduction between the contents of the package and outer atmosphere, and which will be particularly adapted for shipment by air.

2

Applicant has as another object of his invention the provision of an insulated package having inner and outer containers spaced apart by fillers or supports which are so positioned and which cover such areas of strain and load as to prevent rupture, breakdown or sagging of the inner container, and which will obviate collapse of the filler or support.

Applicant has as another object of his invention the provision of an insulated package of the type employing inner and outer containers spaced apart by supports or fillers to provide a space between the containers for insulating purposes, the fillers or supports being of such a size and shape and being so positioned as to facilitate quick, easy and close fitting of the parts of the package so as to obviate jostling or shaking about of the inner container while handling or shipping and to prevent rupture or breakdown of the package.

Applicant has as a further object of his invention the provision of a light weight, sturdy, insulated package made from sheet fibrous or other suitable material, which will offer the requisite strength while providing insulating qualities against transfer of heat between the inside and the outside thereof and which is particularly adapted for use in air cargo transportation of such articles as perishables.

Applicant has as a further object of his invention, the provision of a spacer or filler, which is light in weight, stiff and sturdy in construction and which will be positioned in an insulated package so as to provide a minimum of heat transfer therethrough while being easily adaptable to a close fit with containers it is employed to space apart.

Applicant has as a further object of his invention, the provision of an insulated package which may be quickly and easily assembled and broken down and whose elements fit closely and accurately together to provide a compact structure.

Applicant has as a still further object of his invention, the provision of an insulated package which employs spaced inner and outer containers with provision for a heating or cooling medium in the space to assist in maintaining the desired temperature for the contents of the package.

Other objects and advantages of my invention will appear from the following specification and accompanying drawings, and the novel features thereof will be particularly pointed out in the annexed claims.

In the drawings, Figure 1 is a plan view of my improved package utilizing my improved spacer, employed to space inner and outer cartons. Fig-

ure 2 is a cross section in elevation taken along the lines 2—2 of Figure 1. Figure 3 is a plan view of the blank from which my improved spacer is formed. Figure 4 is a perspective of one of my improved spacers set up for use. Figure 5 is a perspective of my improved spacer partly in section and partly broken down. Figure 6 is a perspective, partly in section, of an outer container employed to house a plurality of inner containers spaced from each other and from the outer container by my improved spacer. Referring to the drawings in detail, A designates a flat sheet or blank of cardboard, paperboard, or other suitable fibrous material having the requisite strength and stiffness. The blank A is divided into a series of sections by transverse crease lines 1, 2, 3, 4, and 5. The end sections of the blank are slit longitudinally at 6, 7, to form arms or upper flaps 8, 9, and legs or lower flaps 10, 11. The central portion of sections 12, 13, is slit longitudinally along a line 14, to provide an upper panel or strap 15, foldable centrally thereof along transverse crease line 3, and at its ends, along transverse crease lines 16, 17. As will be seen from Figures 4 and 5, the blank of Figure 3 is foldable to form a filler or support. In setting up this filler or support, sections 18, 19 are folded rearwardly along crease lines 2 and 4 to form one pair of adjacent sides, and the sections 12, 13, are folded outwardly along the lower part of crease line 3, to form the other pair of adjacent sides. In this latter operation, the ends of panel 15 are folded forwardly towards each other along crease lines 16, 17, and the upper part of crease line 3 to provide a rearwardly extending strap or panel. Leg or flap 11, is folded inwardly along crease line 5, until it engages the blank A at or near crease line 3, and at the same time, arm or upper flap 9, is folded inwardly until it engages the blank A at or near the crease line 11. At or almost simultaneously with this same operation, leg 10 may be folded inwardly until it engages crease line 3 and substantially coincides with and overlaps leg 11. Likewise, arm 8 folds inwardly until it engages crease line 16. While this is a convenient procedure for setting up this filler, spacer or support, it is recognized that other ways may also be conveniently employed.

When the spacer is thus set up, it forms a substantially square structure with the ends of the legs 10, 11, serving to reinforce the lower part of the crease line 3, where it is bent to define the sides 12, 13, and the ends of the arms 8, 9, serving to reinforce the crease lines 16, 17, respectively, where the panel is formed. The legs 10, 11, and the arms 8, 9, serve to provide spacing elements to maintain the various portions of the filler in their proper positions and to stiffen and strengthen the filler as a whole. At the same time, they permit the structure to yield and to change shape sufficiently to accommodate the filler or spacer in the space between the inner and outer cartons, and provide a close and proper fit with the cartons with which they are associated.

The relation of the spacers or fillers to the package, is best disclosed in Figures 1, 2, and 6. The package of Figures 1 and 2 contemplates only a single inner and a single outer container spaced apart by fillers, while Figure 6 contemplates a single outer container and a plurality of inner containers spaced from each other and from the outer container by a series of spacers or fillers.

In general, where only a single inner container

is to be spaced from the outer container, a series of eight spacers are employed, providing a spacer at each of the eight corners of the inner and outer containers. They serve to completely fill the space between the containers at those points and function to maintain the desired spacing. It will be noted that the upper spacers engage the top of the inner container 20 through the inner edges of the sides 12, 13, and along the inner edges of the legs 10, 11. The lower spacers engage the bottom of the inner container 20 through the same portions of the spacer A. The weight of the load of the inner container is thus applied to the spacer through the edges of the sides 12, 13 and the edges of the legs 10, 11. This places the load on the strongest portions of these elements, since this flat material will support and withstand a much greater load applied to its edges than that applied to the flat surfaces. This construction also reduces the area of contact and takes advantage of the higher insulating qualities of this thin material, minimum contact surface, and long path across the open gap or space between containers. The use of the legs 10, 11, as well as the sides 12, 13, as supports, distributes the load over a greater area and provides a stronger filler. The straps or panels 15, will ordinarily receive only side or end thrusts and although they present a considerably greater surface to the inner container, they do not ordinarily engage the inner container throughout their entire length, and, therefore, present a relatively long path from the inner to the outer container, thereby preserving a relatively high degree of insulation, while preventing any appreciable relative endwise or sidewise movement of the containers. While, for purposes of convenience and clarity, the spacers or fillers are shown as engaging only a small portion of the bottom or top of the inner container, it will be understood that with heavier loads, they may extend to almost the center of the bottom or top of the inner container and may cover a very considerable part of these areas, preventing any tendency of the bottom or top of the inner container to sag or become ruptured due to heavy load or lack of support. Also, the fillers may be made rectangular, as well as square configuration when necessary or desired.

When in position, it will be further noted that the sides 18, 19, engage the inner faces of the side or end walls of the outer container at the corners, and that the outer edges of the sides 12, 13, 18 and 19, as well as the outer edges of the legs 10, 11, rest on the bottom or the top of the outer container and distribute the load from the inner container over a considerable area, and through the edges of these elements, which are the strongest portions of the flat material from which they are made.

If desired, a plurality of inner containers may be inserted in the outer container. Figure 6 shows one of such containers located in an outer container 22, having side and end flaps 23, 24, foldable to form a top. Another or others may be set adjacent to the free sides and ends of inner container 20, and like spacers A may be employed to space the inner containers from each other and from the outer container.

It will be understood that perishables or other materials or articles sensitive to temperature changes, may be inserted in the inner container, and that container closed. The inner container may be inserted into the outer container through its top with appropriate spacers A disposed about

the eight corners of the inner container. When this assembly is complete, the top of the outer container may be closed against the top spacers and the package completed.

The inner and outer containers are preferably made from paperboard, cardboard or other fibrous material, molded or formed into flat stock and folded to container configuration. It is also preferred that both inner and outer containers be closed and substantially sealed.

If desired, dry ice or other cooling or heating media may be inserted in the space between the inner and outer containers to supplement the insulating qualities of the package in preserving the contents thereof. Where dry ice or other cooling media are used, they should be placed in the space between the tops of the inner and outer containers in order to permit the cold air to flow downwardly. Where a heating medium is employed, the reverse is true, and that should be placed between the bottoms of the inner and outer containers, so that the heat may rise. These additional media will serve as a temperature control and would preferably be employed on long shipments or where the contents of the inner container is particularly sensitive to a critical temperature range.

It will be further understood, that a series of containers, each within the other, may be used, employing the spacers or fillers disclosed herein, without departing from the spirit of this invention.

While the foregoing package has been primarily directed towards the storage or shipment of perishables, it will be understood that in lieu of the air space between the inner and outer containers, insulating material may be packed therein instead. Furthermore, the package is not limited to the shipment of perishables, but may be employed to ship furniture, breakables or other merchandise by simply substituting the merchandise in question for the inner container. For example, the portions of a table may be supported in spaced relation to a container by the interposition of the spacer disclosed herein between the table or other object and the container.

While the present description sets forth a preferred embodiment of the invention, changes may be made in the construction without departing from the spirit of the invention, and is therefore desired that the present embodiment be considered in all respects as illustrative and not restrictive, reference being had to the appended claims rather than to the foregoing description to indicate the scope of the invention.

Having thus described my invention, I claim:

1. A package of the character described comprising a container, a body disposed within said container, and means for supporting said body in spaced relation to said container, said means including a spacer made from a single blank of foldable material to form two pairs of adjacent sides, a panel struck from the upper portion of one of said pairs of adjacent sides and bendable inwardly to provide a strap for engagement with said body to limit sidewise and endwise movement thereof, a pair of lower flaps joined to the meeting edges of the other pair of adjacent sides to reinforce it, and a pair of upper flaps joined to the meeting edges of the other pair of adjacent sides for engagement with the junctures of said panel with the first set of adjacent sides, the edges of the cut away sides cooperating with the edges of the lower flaps to support said body.

2. A package of the character described comprising a container, a body within said container, and a spacer interposed between said container and body, said spacer being made from a single blank of material foldable to provide a body portion of substantially rectangular configuration with pairs of adjacent sides, a panel struck from the upper intermediate portions of one pair of sides, said panel folded inwardly to provide a strap for engagement with the body to limit its sidewise and endwise movements, lower flaps joined to the meeting edges of the other pair of sides and foldable inwardly to provide reinforcement for the juncture of the said first pair of sides, the edges of the cut away portions of said first pair of sides engaging the body and serving to support it in spaced relation to the outer container.
3. A package of the character described comprising an outer container, an inner container disposed within said outer container, and a spacer interposed between said inner and outer containers, said spacer being formed from a single blank of material foldable to form a body having pairs of adjacent sides, a panel struck from the upper intermediate portions of one of said pairs of sides and foldable inwardly to define a strap for engagement with said inner container to limit endwise and sidewise movement thereof, upper and lower flaps joined to the meeting edges of the other pair of said sides, said upper flaps being foldable inwardly to reinforce the junctures of the panel and sides, said lower flaps being foldable inwardly to reinforce the juncture of the first of said pairs of sides, said lower flaps and the cut away portions of the first pair of said sides being engageable with the inner container through their edges to support said inner container in spaced relation to said outer container.
4. A tri-directional spacing element formed of foldable material, comprising a plurality of walls including a pair of angularly related connected walls having portions adjacent their connected ends of less transverse extent than the portions adjacent their remote ends, a strap connected at each end to the wall portions of greater extent and bent inwardly of the angle between said pair of walls, a third of said plurality of walls extending partially across the angle between said pair of walls, a bracing flap hinged on said third wall and extending to a connection between said strap and pair of walls, and a reinforcing flap also hinged on said third wall and extending to the connection between said pair of walls.
5. A blank for a spacing element, comprising a sheet of foldable material cut and scored to define a plurality of serially connected wall panels including a pair of hingedly connected panels of greater extent adjacent their remote ends than adjacent their connected ends and a third panel hingedly connected to one of said pair of panels, a strap extending between and hingedly connected at its ends to the portions of greater extent of said panel pair and defined from the portions of lesser extent thereof by a slot, and a flap hingedly connected to said third panel, said flap lying between lines of extension of the edges of said portions of lesser extent of said panel pair and having a length corresponding to that of the hypotenuse of a right triangle the other two sides of which have lengths corresponding to the lengths of the panels of said panel pair.
6. A blank for a spacing element, comprising a sheet of foldable material cut and scored to define a plurality of serially connected wall panels

including a pair of hingedly connected panels of greater extent adjacent their remote ends than adjacent their connected ends and a third panel hingedly connected to one of said pair of panels, a strap extending between and hingedly connected at its ends to the portions of greater extent of said panel pair and defined from the portions of lesser extent thereof by a slot, and a flap hingedly connected to said third panel, said flap lying at least partially between lines of extension of the edges of said portions of greater extent and having a triangle the other two sides of which have lengths corresponding to the distances from the connection between said third panel and said one panel of said panel pair, respectively to the adja-

cent end of said strap, and to the connection between said flap and said third panel.
